Dec. 1694

Julius Holzer, of Philadelphia Penn.
assignor to
E. W. Maragle of Philadelphia Penn.
Letter Patent No. 1694 - Dated. Decr 16. 1863.

The schedule referred to in these Letters Patent and making part of the same.

To all whom it may concern:

Be it known that I, Julius Holzer, of the City of Philadelphia in the state of Pennsylvania, have invented or produced a new and original Design for stove plates; And I do hereby declare that the following is a full and exact description of the same, reference being had to the accompanying drawings, making a part of this specification, in which figure 1, shows a front view of the said design applied to a stove-door plate; And figure 2 a transverse section of the same.

The whole of this ornamental design is contained within the usual boundary moulding, or frame, of the plate; and consists of

Des. 1696

raised and depressed portions, producing ornamental configurations upon the face of the plate - the latter being raised toward its middle as represented in the drawings and herein after specified.

In the said drawing A, is a middle ornament having four radiating stems b. b. b. b. each stem terminating in a lanceolate point, or leaf, c. between scrolls d. d. and e. e. each of which latter having a convex head, f. Between the radiating stems b. b. b. b. and adjoining the middle ornament A, there are four distinct plain surfaces g. g. g. g. and apparently projecting from beneath these latter, respectively, are four bunches or groups of lanceolate leaves H. I. I. H. H. substantially as represented in figure 1.

Although the described design is shown as a ornament for a doorplate, it is equally appropriate, and intended also, for the door outside plates of a stove.

What I claim as my invention or production, and desire to secure by letters patent, is,

The configurations described and specified, as an ornamental design for door plates.
